Primary Examiner — Cynthia Ramirez*Assistant Examiner* — Laura H Yu(74) *Attorney, Agent, or Firm* — Troutman Sanders LLP; Ryan Schneider; Chris Davis(57) **CLAIM**

The ornamental design for a gel cushion insole, as shown and described.

DESCRIPTION

FIG. 1 is a perspective view of our new design for a gel cushion insole;

FIG. 2 is a left side elevation view thereof;

FIG. 3 is a right side view thereof;

FIG. 4 is a front elevation view thereof;

FIG. 5 is a back elevation view thereof;

FIG. 6 is a top plan view thereof; and,

FIG. 7 is a bottom plan view thereof.

The broken lines are included for the purpose of illustrating portions of the gel cushion insole that forms no part of the claimed design.
